UNITED STATES PATENT OFFICE.

BROOKS M. TRAUGER, OF SCRANTON, PENNSYLVANIA.

HOOF PAD.

Application filed May 16, 1921. Serial No. 470,168.

To all whom it may concern:

Be it known that I, BROOKS M. TRAUGER, a citizen of the United States, residing at Scranton, in the county of Lackawanna and 5 State of Pennsylvania, have invented certain new and useful Improvements in Hoof Pads; and I do declare the following to be a full, clear, and exact description of the invention, such as will enable others skilled in 10 the art to which it appertains to make and use the same.

My invention relates to improvements in hoof pads and more particularly to those formed of rubbered fabric and rubber, 15 formed as an integral unit with a rigid horseshoe. In the manufacture of devices of this character, difficulty has been encountered in properly securing the rubbered fabric to the horseshoe, and the principal object of my invention is to provide a novel 20 construction which will overcome the difficulties heretofore existing.

Another object of the invention is to provide a rubber pad with a convex lower side 25 and a planar upper face, the latter being vulcanized to non-stretching fabric which is anchored at its edge portions to the shoe. This construction permits considerable upward yielding of the rubber pad when in 30 use and therefore prevents excessive wear thereof, but the non-stretching fabric prevents the pad from bulging upwardly to such an extent as to produce undesirable pressure against the frog of the animal's 35 foot.

With the foregoing in view, the invention resides in the novel construction hereinafter described and claimed, the description matter being supplemented by the accompanying 40 drawing.

Figure 1 is a perspective view of a complete pad constructed in accordance with my invention.

Fig. 2 is a perspective view of the partly 40 completed device,

Fig. 3 is a perspective view showing a further step in the construction of the device, and

Figs. 4 and 5 are sectional views as indicated by lines 4-4 and 5-5 respectively of Fig. 1.

In the drawing above briefly described, the numeral 1 designates a rubber pad which is co-extensive with the hoof on which it is 55 to be used, said pad having a planar upper surface 2 and a convex lower side 3, said pad

being suitably recessed as indicated at 4 to provide it with an anti-slipping tread surface. Resting on the planar surface 2 of the pad 1 and vulcanized thereto, is a sheet of 60 non-stretching rubbered fabric 5 which is preferably formed of two plies, the edge portions of the sheet being notched at intervals as indicated at 6, and being folded inwardly around a rigid horseshoe 7 which 65 rests on the sheet 5, said folded edge portions being vulcanized to the central portion of the sheet, that is the portion within the shoe 7. A top sheet 8 of non-stretching rubbered fabric, preferably three-ply, is vulcanized 70 to all of the upwardly exposed portions of the sheet 5, said sheet 8 being co-extensive in size with the shoe 7.

In the manufacture of the shoe, the pad 1 is first molded from green rubber, the 75 sheet 5 is then applied to the upper surface of said pad, and the shoe 7 and a rubber filler 7^a between its ends are placed upon said sheet. The edge portions of the sheet are now notched as at 6, or they may be 80 notched at some prior time, and said edge portions are folded inwardly around the shoe 7 and the filler 7^a onto the central portion of the sheet. A thin sheet of green rubber is then placed over the upwardly exposed 85 portions of the sheet 5, and to this sheet of rubber, the top sheet 8 is applied. The entire device is then placed in a hydraulic press and vulcanized so that a single 90 unitary structure is produced, in which the shoe 7 is effectively anchored to the pad 1. The thin sheet of green rubber above referred to, is not shown between the inwardly turned portions of the sheet 5 and the top sheet 8, as in the completed article 95 the rubber permeates the fabric instead of remaining in the form of a distinct sheet.

The edge portion of the pad 1 is suitably cut away at 9 to permit the attaching nails to be driven through the usual openings 10 100 in the shoe 7. Before the device is attached to the hoof however, if it is desirable, the pocket 11 formed in its upper side is filled with tarred oakum or other suitable material having a curative or antiseptic effect 105 upon the hoof.

Attention may here be directed to the fact that the convex lower side of the pad 1 causes upward yielding of the central portion of the pad each time weight is placed 110 thereon, so that wear is reduced to the minimum, it having been found that if no

yield is permitted, the tread surface of the pad will soon wear entirely off. Attention is further invited to the fact that the non-stretching fabric used in the manufacture 5 of the device, will not permit the central portion of the pad to spring or bow upwardly to such an extent as to exert undesirable pressure upon the frog of the animal's foot. The fabric can yield upwardly 10 to a slight extent only, and when this limit is reached, the rubber of the pad is yieldably compressed as it supports the weight. Since excellent results have been obtained from the details disclosed, these 15 details are preferably followed. I wish it understood however that within the scope of the invention as claimed, numerous minor changes may be made. If desired, the portions of the sheet 5 at the outer edge of the 20 shoe 7 and filler 7^a, may be rubber-coated as seen in Figs. 4 and 5.

I claim:

1. A device of the class described comprising a rubber tread pad, a sheet of fabric vulcanized on the upper side of said pad, and a rigid horseshoe resting on said sheet, the edge portions of the sheet being folded inwardly around the shoe and vulcanized to the central portion of said sheet.
2. A device of the class described comprising a rubber tread pad, a sheet of fabric 30

vulcanized to the upper side of said pad, a rigid horseshoe resting on said sheet, the edge portions of the sheet being folded inwardly around the shoe and vulcanized to 35 the central portion of said sheet, and a top sheet of fabric substantially coextensive with the shoe and vulcanized to the upwardly exposed portions of the aforesaid sheet.

3. A device of the class described comprising a rubber tread pad having a planar upper surface and a convex lower side, a sheet of non-stretching fabric vulcanized on 40 said planar upper surface of said pad, and a rigid horseshoe resting on said sheet, the edges of said sheet being folded around said 45 shoe and vulcanized to the central portion of said sheet.

4. A device of the class described comprising a solid rubber tread pad having a planar upper surface and a convex lower side, a planar sheet of non-stretching material secured on said planar upper surface of said pad, and a rigid horseshoe resting 50 on said sheet and secured with respect thereto, whereby said sheet non-stretchably spans the shoe and prevents bowing of the pad to an undesirable extent.

In testimony whereof I have hereunto set 60 my hand.

BROOKS M. TRAUGER.
